UNITED STATES PATENT OFFICE.

ALBERT GIEGERICH, OF DUBUQUE, IOWA.

DEVICE FOR ADVERTISING.

1,111,957.

Specification of Letters Patent. Patented Sept. 29, 1914.

Application filed May 26, 1913. Serial No. 769,857.

To all whom it may concern:

Be it known that I, ALBERT GIEGERICH, a citizen of the United States, residing at Dubuque, in the county of Dubuque and State of Iowa, have invented certain new and useful Improvements in Devices for Advertising, of which the following is a specification.

My invention relates to advertising devices for displaying goods, more especially in store windows, and the object is to provide a machine which shall be adapted to be rotated whereby various kinds of goods may be brought into view one after another and held in displayed position for a predetermined length of time.

In what it consists and the mode of construction whereby I accomplish the object sought will be fully described and illustrated in the following specification when read in connection with the drawings accompanying the same and forming a part hereof, in which—

Figure 1 is a perspective view of the endless carrier. Fig. 2 is a front view of the device with the panels attached to the carrier with advertisements on the facings. Fig. 3 is a top view with cap removed. Fig. 4 is a bottom view. Fig. 5 is a vertical section through the longitudinal center. Fig. 6 is a plan view of one of the sprocket wheels. Fig. 7 is a plan view of a plate for holding a panel on the carrier. Fig. 8 is a perspective view of a panel and shows means for attaching and rotating the panels. Fig. 9 is a perspective view of the means for locking the panels together when the panels are at rest.

Referring to the drawings, 2 designates the endless carrier which consists of strips 4 and 7. To each strip 4 is secured two plates 5 and 6; shown in Fig. 7, one near the top and the other near the bottom, that are each provided with a slot 8, into which a panel hereinafter to be described is removably secured. Between the strips 4 are spacing strips 7 which are hinged to the strips 4, thus making every other strip carry a panel and the strips 7 blanks without anything thereon and all hinged together by hinges 3, as shown in Figs. 5 and 6. In the rear of each strip 4 and 7 is a recess 10 near the top and also a like recess 12 near the bottom which is adapted to be engaged by a dowel connected with a wheel hereinafter to be described. At the bottom of each strip 4 is

pivoted a caster-wheel 13, which is adapted to travel in a groove in a track 17.

The panel 15, to be secured to the strip 4 shown in Fig. 2, consists of a rectangular frame which may be covered with cloth or beaver board or anything else that presents a smooth surface for use in displaying wall paper and paint brushes and the like as set forth in this application. Where it is used for other purposes there may be a frame and hooks 19 thereon, as shown in Fig. 8. The rear edge of the panel 15 has large headed screws 16 which are adapted to engage in the slots 8 in the two plates 5 and 6 set in the strip 4. By this mode of attaching the panels to the strips the panels 15 are removably and loosely held to the strip 4.

To the outer edge of the panel 15 is secured a facing 18 of the width of the strips 4 and 7 so that when these panels are assembled and ready for use, they will present an unbroken surface upon which may be painted the name of the house that is selling the goods or any other advertisement. A convenient mode of using this surface is by marking one letter of a word upon each of the facings 18 in the same plane, then in a lower plane another set of letters spelling out other word or words and so on down the facings and each word commenced in a different vertical plane, then when a certain number of facings are brought to view, there would appear a whole word and parts of other words and as the carrier advanced that word would gradually disappear and more of other words come into view so that at all times there would be one whole word and parts of other words in sight. In the drawing the two letters P and A shown in dotted lines represent the letters "P" and "A" on two vanished facings and "INT" in full on three facings in view, the whole spelling the word "paint." Where these panels are to be used for displaying wall paper the panel

has pasted upon it a pattern of wall paper 20 with the border 22 and presenting the same appearance as it would if the paper were actually pasted upon a wall, and if it is used for hanging paint brushes or other articles, there are hooks 19 attached to this panel and the brushes are hung thereon.

For the purpose of rotating this device there is provided a shaft 28, shown in Fig. 6, which is provided with a circular plate 30 having dowels 32 adapted to engage the recess 10 in the strips 4 and 7. In the plate 30

there are also semicircular recesses 34 into which the hinges 3 are adapted to engage when the carrier is being turned around with the shaft 28. The shaft 28 is provided at the end with a circular pin 35 which is adapted to rotate in a box 36 in a top plate 37. At the bottom of the shaft 28 there is a similar head 30 with similar dowels 32 that are adapted to engage the recesses 12 in the strips 4 and 7. At the other end there is a similar means for rotating, but in addition there are secured to the rotating shaft arms 40, the object of which will presently appear.

In order to rotate the endless carrier intermittently and bring the panels one after another into position for inspection and keep them in that inspecting position for a predetermined length of time, there is provided a wheel 42 upon which are placed pins 44. The wheel 42 is belted to power and as it rotates, the arms 40 are engaged by the pins 44 and rotate the carrier a short distance sufficient to bring one of the panels on each side into view as shown in Fig. 2.

For the purpose of closing and locking the panels together at the front, so that they will present an apparently unbroken face at each interval of rest in its rotation, there is attached to the underside of the wheel 42 a plate 48, (see Figs. 4 and 9) beveled at one end, which is adapted, when the wheel is rotated, to engage the upper surface of a lever member 50. This member consists of an arm 52 pivoted to the frame of the device by a pivot pin 54. To the arm 52 is attached a second arm 55 that is provided with a lug 56 at its outer end and is pivoted to the frame by a pivot pin 58. Against a stud 60 mounted on the arm 52 is secured a leaf spring 62 that is bent down and adapted to engage the upper surface of the arm 52.

The manner of operating my device is substantially as follows: Starting with the carrier 2 set in its proper position, the operator takes one of the panels 15 upon which is pasted the paper 20 or the other articles and brings the screws 16 into engagement with the slots 8 in the plates 5 and 6, and forces it down to the bottom of the slots. The caster wheel 13 on the bottom of the strip 4 will then set in the groove in the track 17. The rest of the panels are placed in the strips 4 in the same manner until every other strip has a panel attached thereto. Then the carrier will have a panel on each of the strips 4 and nothing attached to the strips 7, and there will necessarily be a space between the panels in the rear ends but, since there is a facing 18 on the front end of each panel, that is wider than the thickness of the panel, when the panels are all in place, there will be presented a connected surface of facings 18 on which may be painted any advertisement desired. After

all of these panels are placed in position and are ready for operation, there will be a panel at each side projecting out at right angles and the other panels closed together both in front and rear of the carrier as shown in Figs. 2 and 3. The power is then turned on to the wheel 42 and as it rotates the pins 44 will engage the arms 40 and turn them partially around and since they are attached to the wheel, they will rotate the carrier a short distance sufficient to close up the panels that project from the sides and throw into the same position two other panels. In this manner one panel from the side will be folded back and a panel from the front will take its place while the other side panel will be closed up against the front panels and a new panel from the rear will be brought into its place. While the wheel is rotating, just before the pins 44 are brought into engagement with the arms 40, the plate 48 will engage the lever 52 which will raise the rear end of the arm 54 and this will draw down the lug 56 out of engagement with the base of a panel and release the panel and permit it to be brought into view and as soon as it is released the plate 48 will be brought out of contact with the arm 52 and the spring 62 will come into action and bring the lug 56 into engagement with the next panel and close together the facings 18 and hold all the remainder of the panels close together thereby presenting an unbroken front and rear with a panel projecting out from each end. The wheel will then continue to rotate until another pin 44 comes in contact with another arm 40 but during this time the carrier and the panels will remain in a resting position.

It will be seen by this mode of construction and operation that all of the panels, one after another, on each end of the carrier will be brought into view and will stay in that position for a predetermined length of time according to the rapidity of the rotation of the wheel 42 and since the panels are loosely attached to the strips while the panels are traveling, the faces 18 become separated and when the lug 56 engages a panel, the carrier with the panels will travel sufficiently farther to close up the face 18 and present a front having the appearance of an unbroken surface, and since a letter of an advertisement is painted on each face 18 the whole advertisement may be readily read while the carrier is at rest.

Having now described my invention what I claim is:—

1. In a device of the character described, panels, an endless carrier consisting of strips of greater length than the panels hinged together, means connected with alternate strips and each panel for removably attaching the panels to the strips, means for intermittently advancing the panels, and means

engaging one of the panels for holding part of the panels in a predetermined position for a predetermined length of time.

2. In a device of the character described, 5 an endless carrier consisting of strips hinged to each other, panels removably attached to alternate strips of the carrier, facings of the width of two strips of the carrier on the outer longitudinal edge of each panel, means 10 for intermittently advancing the carrier and means for stopping the carrier and bringing the facings on the edges of the panels on one side of the carrier in contact with each other.

15 3. In a device of the character described, an endless carrier composed of strips provided with recesses hinged together, panels provided with facings on their outer longitudinal edges, means for removably attaching 20 the panels to alternate strips of the carrier, means for imparting motion to the carrier consisting of a plurality of shafts set vertically within the carrier, wheels on the shafts and provided with means adapted 25 to engage the recesses in the strips of the carrier, means connected with power and one of the shafts to cause the carrier to travel intermittently around the shafts, and means for stopping and holding the panels 30 in a given position at predetermined times.

4. In a device of the character described, an endless carrier, panels secured to the carrier, facings on the outer edges of said panels, means for imparting an intermittent motion to the carrier, and means for holding said facings on the panels on one side of the carrier in contact with each other at and for a predetermined time.

5. In a device of the character described, 40 an endless traveling carrier composed of strips set vertically and hinged together, and said strips provided with recesses, two shafts set vertically, a wheel on each shaft and the wheels provided with dowels adapted 45 to engage the recesses in the strips and rotate the carrier around said shafts, panels removably attached to alternate strips of the carrier, and said panels having abutting extremities certain of which are brought 50 into contact with each other for display purposes when two panels are diametrically opposite of each other, and means for holding said certain of the panels in contact with each other for a predetermined length of 55 time.

6. In a device of the character described, a carrier composed of strips hinged together, a caster on the bottom of alternate strips, a track beneath the carrier on which 60 the casters carrying the carrier travel, panels removably secured to alternate strips of the carrier, a facing secured to the edge of each panel of such width that when the panels are folded together the facings will 65 contact with each other, and means for im-

parting an intermittent motion to the carrier.

7. In a device of the character described, 70 an endless traveling carrier consisting of strips hinged together and each strip provided with a recess, panels adapted to be removably and loosely held by the strips, a plurality of shafts vertically set within the carrier, casters attached to the strips at the base of the carrier, a track around the shafts 75 and parallel with the travel of the carrier, wheels on the shafts adapted to engage each of the recesses of the strips of the carrier, means connected with one of the shafts for causing the carrier to travel intermittently on the track around the shafts, and a stop adapted to be brought into engagement with a panel to stop the advance of the panels at a predetermined time.

8. In a device of the character described, 80 a carrier composed of strips hinged together, panels removably attached to alternate strips of the carrier, means for imparting an intermittent motion to the carrier, and means for stopping the panels at a predetermined time and holding them in a predetermined position when the carrier is at rest.

9. In a device of the character described, 85 a carrier composed of strips hinged together, panels removably attached to alternate strips of the carrier, means for imparting to the carrier an intermittent motion, means for stopping and holding the panels for a predetermined length of time, and for closing part of the panels together 90 on one side of the carrier.

10. In a device of the character described, 95 a carrier composed of strips hinged together, panels removably attached to alternate strips of the carrier, facings on the panels, two shafts set vertically, means connected with the shafts and engaging the strips of the carrier for rotating said carrier around said shafts, means for stopping the carrier when two panels on opposite 105 ends of the carrier are in the same vertical plane, means for stopping and holding the panels on one side of the carrier at right angles to the projecting panels with 110 their facings in contact with each other when the carrier is at rest.

11. In a device of the character described, 115 a carrier composed of strips hinged together, panels removably attached to alternate strips, facings on the longitudinal outer edges of the panels, means for imparting to the carrier an intermittent motion, means engaging one of the panels for bringing the facings of part of the panels in contact with each other, and means for stopping the travel of the panels at a predetermined time.

12. In a device of the character described, 120 a carrier composed of strips hinged together, panels removably and loosely attached to 125

130

alternate strips and provided with facings, means for imparting to the carrier an intermittent motion, and a lever operated by the means for imparting motion to the carrier to engage the panels and stop their advance and hold part of the panels with their facings in contact with each other.

13. In a device of the character described, a carrier composed of strips hinged together and alternate strips provided with a plurality of plates having slots therein, panels provided with means for removably engag-

ing the slots in the plates attached to the strips, means within the carrier for imparting motion to the carrier, and means engaging the panels for stopping the travel of the panels at predetermined times. 15

In testimony whereof I affix my signature in presence of two witnesses.

ALBERT GIEGERICH.
